CLOTHES HANGER

Charles Mallett, Chula Vista, Calif.

Application August 3, 1951, Serial No. 240,139

2 Claims. (Cl. 223—91)

1

This invention relates to improvements in clothes hangers, and more particularly to improved clothes hangers of the type having a clamping arm adapted to engage a garment and secure the garment on the hanger.

A main object of the invention is to provide a novel improved clothes hanger of the garment-clamping type, which is simple in construction, which is easy to manipulate, and which provides secure clamping action with respect to the garments held thereby, so that said garment will not slip from the hanger.

A further object of the invention is to provide an improved garment hanger of the garment-clamping type which is inexpensive to manufacture, which is compact in size, which is neat in appearance, and which is rugged in construction.

Further objects and advantages of the invention will become apparent from the following description and claims, and from the accompanying drawings, wherein:

Figure 1 is a front elevational view of an improved garment hanger constructed in accordance with the present invention;

Figure 2 is an end elevational view of the garment hanger of Figure 1;

Figure 3 is a horizontal cross-sectional view taken on the line 3—3 of Figure 1;

Figure 4 is a cross-sectional view taken on the line 4—4 of Figure 2;

Figure 5 is a fragmentary front elevational view of the lower portion of the garment hanger of Figure 1, showing the clamping bar in released position;

Figure 6 is an enlarged perspective detail view of the resilient connecting hook employed to connect the ends of the bar elements of the improved garment hanger;

Figure 7 is a perspective view of the resilient bail member employed to resiliently lock the lower bar member in clamping position with respect to the upper bar member.

Referring to the drawings, the improved garment hanger is designated generally at 11 and comprises a pair of wire members 12 and 13 twisted together at 14, the end of one of said wire members being formed with the hook 15. Designated at 16 is a first rigid bar member of any suitable material, such as plastic material or the like, the lower ends of the wire members 12 and 13 being embedded in the respective end portions of the bar member 16, as shown in Figure 4. The bottom surface of the bar member 16 is formed with the elongated, longitudinal, downwardly facing groove 17, said groove being sub-

2

stantially semicircular in cross-sectional shape. Designated at 18 is a cylindrical bar member of suitable rigid material, such as plastic material and the like which is receivable in the groove 17.

5 The bar members 16 and 18 are formed adjacent their left ends, as viewed in Figure 4, with openings 19 and 20 which are registrable, as shown in Figure 4, and which communicate with respective grooves 21 and 22 formed in the end portions of the bar members 16 and 18 to define a continuous seat in which is positioned a resilient C-shaped connecting member 23. The ends of the connecting member 23 are engaged in the openings 19 and 20, as shown in Figure 4, and the body of the connecting member is seated in the grooves 21 and 22, whereby the ends of the bar members 16 and 18 are resiliently connected together.

The upper bar member 16 is formed at its right end, as viewed in Figure 1, with a pair of transverse bores 24 and 25 in which are pivotally engaged the ends 26 and 27 of a resilient bail member 28, the side arms of the bail member 28 being bent to substantially V-shape, as shown in Figure 7, and the loops 29 and 30 of said side arms exerting resilient clamping pressure on the upper bar member 16. The right end portion of the lower bar member 18, as viewed in Figure 5, is formed with a peripheral groove 31, and the bight portion of the bail member 28 is movable into a position in which it lockingly engages in the groove 31, as shown in Figure 1. The bight portion of the bail member 28 may be disengaged from the groove 31 by exerting downward force on the loops 29 and 30 whereby the bail member 28 may be distorted to disengage the bight portion thereof from the groove 31 and to swing the bail member outwardly to a position thereof, such as is shown in Figure 5, whereby the lower bar member 18 will be released.

40 With the lower bar member 18 in a released position, such as shown in Figure 5, a garment, such as a pair of trousers, may be engaged over the lower bar member 18 and may be securely clamped to the hanger by moving the lower bar member 18 into the groove 17 and locking the right end of the lower bar member by swinging the bail member 28 downwardly to a position wherein the bight portion engages in the peripheral groove 31 in the lower bar member. The trousers will then be securely clamped to the hanger, and will not be marred or creased by the hanger in view of the curved shape of the opposing clamping surfaces provided on the upper and lower bar members 16 and 18. The re-

mainder of the hanger may be employed for supporting a coat or jacket in the usual manner. To remove the pair of trousers or other garment secured to the hanger, it is only necessary to release the lower bar member by disengaging the bail 28 therefrom, whereby the garment may be slid out from between the bar members 16 and 18.

While a specific embodiment of an improved clothes hanger has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A clothes hanger comprising a hook, a first bar member, means connecting said hook to said first bar member, a second bar member, a resilient C-shaped member having its ends engaged in the end of each bar member, said ends of the bar members being formed with registering grooves receiving said C-shaped member, whereby said C-shaped member yieldably connects said ends of the bar members, and a bail member pivotally secured to the other end of said first bar member and being arranged to lockingly engage beneath the other end of said second bar member to secure the second bar member adjacent the first bar member, said first bar member being formed with a longitudinal groove facing and adapted to receive said second bar member, said bail member having opposing resilient V-shaped side arms arranged to clampingly engage said first bar member.

2. A clothes hanger comprising a hook, a first bar member, means connecting said hook to said first bar member, a second bar member, a resilient C-shaped member having its ends engaged in one end of each bar member, said ends of the bar members being formed with registering grooves receiving said C-shaped member, whereby said C-shaped member yieldably connects said ends of the bar members, and a resilient bail member pivotally secured to and frictionally engaging the other end of said first bar member and being arranged to be swung into locking engagement beneath the other end of said second bar member to secure said second bar member adjacent the first bar member, said bail member having opposing resilient V-shaped side arms arranged to clampingly engage said first bar member, said other end of said second bar member being formed with a peripheral groove adapted to receive said bail member, said second bar member being circular in cross section and said first bar member being formed with a longitudinal groove of arcuate cross sectional shape facing and adapted to receive said second bar member.
